Filed Oct. 28, 1960, Ser. No. 62,666

Term of patent 14 years

(Cl. D6—2)

FIG. 2.

FIG. 1 on the drawing is a top perspective view of an album showing my new design, the side opposite thereto being plain and unornamented.

FIG. 2 is an edge view of the album shown in FIG. 1. The essential features of my design reside in the parts shown in solid lines on the drawing.

I claim:

The ornamental design for an album, as shown and described.
